UNITED STATES PATENT OFFICE.

ISAAC NEWTON MORFORD, OF ATLANTA, ILLINOIS.

WIRE-FENCE MACHINE.

Application filed November 12, 1921. Serial No. 514,762.

To all whom it may concern:

Be it known that I, ISAAC N. MORFORD, a citizen of the United States, residing at Atlanta, in the county of Logan and State 5 of Illinois, have invented a new and useful Wire-Fence Machine, of which the following is a specification.

This invention relates to wire fence machines, and the features shown and described 10 in the present application are designed as improvements on the structures disclosed in patents numbered 821,112; 851,955 and 963,620, heretofore granted to me.

The object is to provide a wire fence machine of the hand operated type for rigidly fastening the vertical stay wires to the horizontal or longitudinal line wires in a manner to prevent their lateral movement thereon, and at the same time avoid any separating 20 movement of the line wires, the machine being in the form of a readily portable frame adapted to be detachably connected to the line wires in a separate position for each stay, the line wires being previously secured 25 in proper position to the fence posts at the desired distances apart, such distances usually varying from top to bottom of the fence.

Another object is to provide improved 30 means for slidably securing one side of the machine frame to the said line wires by means of engaging members which permit the wire to slide therethrough, and which may be readily adjusted in a vertical direction 35 to adapt the same to the particular spacing of the line wires, the other side of the machine frame having a vertically sliding clamping member for engaging over one of the line wires and adapted to hold 40 that side of the frame to its work upon the fence.

A further object is to provide means carried by the frame extending from side to side of the same and having means for engaging 45 spaced stay wires initially placed in embracing relation to the line wires and adapted to hold the same while the upper and lower ends are twisted about the top and bottom line wires, the intermediate line wires being 50 rigidly held to the stays by opposed twists formed in the latter between each pair of line wires by means of a special tool for the purpose; and a still further improvement resides in the provision of a tool holder carried 55 by the frame of the machine.

A full and complete understanding of the

invention may be obtained from a consideration of the following detailed description taken in connection with the accompanying drawings forming part of this specification, 60 it being understood that while the drawings show a practical form of the invention, the latter is not confined to strict conformity therewith, but may be changed or modified, so long as such changes or modifications 65 mark no material departure from the salient features of the invention, as specifically pointed out in the appended claims.

In the drawings, in which similar reference characters designate corresponding 70 parts throughout the several figures:—

Fig. 1 is a front elevation of the improved machine shown attached in operative position to a wire fence.

Fig. 2 is a central vertical section through 75 the machine.

Fig. 3 is an enlarged horizontal sectional view of the same.

Fig. 4 is an enlarged detail vertical sectional view through a portion of the frame 80 bar having the vertically adjustable line wire-engaging members attached thereto.

Fig. 5 is a similar view of a portion of the other frame bar carrying the aforesaid clamping member attached thereto.

Fig. 6 is a top plan view of said clamp and showing its relation to the adjacent frame bar and the line wire.

Fig. 7 is a detail vertical sectional view through the several line wires together with 90 their holding means, and showing the spaced vertical wires as initially placed for twisting together to form the fence stay.

The machine of the present invention is adapted to build wire fences of any desired 95 height, within the limits of the machine, and of any desired number of line wires spaced uniformly or varying distances apart, depending upon the kind of stock to be confined by the fence. An advantage to be 100 found in the use of fences built by machines of this class resides in the fact that the vertical stay wires may be spaced any desired distance apart, the method of securing the said stays to the top and bottom line wires, 105 and of afterwards twisting the said stays in a manner to stiffen the same and to rigidly support the line wires apart, serving to produce a rigidly constructed fabric, capable of withstanding great strain, when properly 110 attached to supporting posts, and of out-wearing generally the ordinary machine

made, woven wire fabric fence to be found on the market.

- The machine comprises a frame structure including spaced, normally vertical side bars or posts 1, preferably formed of stout, steel tubing of suitable diameter to provide the necessary strength for the purpose, and of a length somewhat greater than the height of the highest fence it may be desired to build.
- 10 A plurality of cross members in the form of yokes 2, formed of steel castings or, if preferred, of appropriate forgings, are adapted to rigidly hold the said posts or bars 1 in spaced relation. These yokes, preferably three in number, are arranged for convenience, one adjacent to the bottom ends of the bars 1, and the other two yokes are placed and held near the upper ends of the same, each yoke consisting of terminal collars 3 integrally formed therewith and of the proper internal diameter to freely slide over the bars 1, suitable set screws 4 being carried thereby for holding them in adjusted position thereon.
- 15 The yokes each comprise oppositely curved arms 5 extending from the rear sides of the collars 3 and curving forwardly at the center, where they merge into a single forwardly-extending arm 6, the forward end 20 of which extends slightly in advance of the front sides of the collars 3, and is provided with a terminal bifurcation 7, open toward the front, and having the side walls of the same slightly curved toward one side of the frame, as clearly shown in Fig. 3 of the drawing. The curved arms 5 of the yoke as well as the forwardly extending central arm 6 are preferably formed diamond shape in cross section, with the greatest dimension 25 thereof arranged vertically, as shown in Fig. 2, in order to provide great strength for resistance to any torsional strain to the parts, while under the severe pressure brought about by the twisting of the stay wires in 30 a manner to be explained.

While the yokes 2 are arranged with relation to the height of the fence and the length of the frame bars 1, as illustrated and heretofore explained, it will, of course, be apparent that the same may, by loosening the set screws 4, be raised or lowered thereon to suit the demands, and that more than three yokes may be employed.

The frame of the machine is adapted to be placed against the corresponding sides of the line wires A of the fence with the bars 1 in vertical position and abutting against each line wire when the bifurcations 7, which comprise stay wire holders, extend 55 slightly through and forward of the line wires.

One of the said bars 1 is provided with a flat bar 8 rigidly carried thereby and spaced from the same on the side corresponding 60 to the bifurcation 7 and in position to abut

against the line wires, the said bar 8 being held in such spaced relation by space blocks or washers 9 surrounding suitable bolts 10 which traverse aligned openings in the walls of the tubular posts 1 and the said bar 8, 70 which latter is also provided with a central, longitudinal series of perforations 11 extending from the lower end to the top thereof.

A series of hook-shaped bolts 12 having a 75 straight, screw-threaded stem or shank adapted to fit any desired one of the perforations 11 is carried by the bar 8, and said bolts are prevented from accidental displacement therefrom by nuts 13 which permit of the hooks swinging about the axis of the stem thereof, the other free end of the same extending at an angle to one side of the bar and slightly to the rear of the same, as clearly shown in Fig. 4, so that, 80 by flexing the line wires A, upon applying the machine in position for use, the said wires may be introduced within the hooks without removing the nuts 13, and the same will not accidentally become detached therefrom, while freely permitting of the sliding action of the machine along the several line wires.

In addition to serving as a means for supporting the bolts 12, the bar 8 has the additional advantage of stiffening the adjacent post 1, as the said posts are subjected to great strain when the stays are formed in a manner about to be described.

The opposite side of the machine frame 100 is held against the fence by means of a vertical slideable sleeve 14 formed of suitable tubing of an internal diameter somewhat greater than the exterior diameter of the other post 1, and mounted on the latter, 105 preferably between the two upper yokes, and having a downwardly directed tongue 15 having oppositely beveled or tapered edges 16, which cause a wedging action on the line wire A located adjacent to the intermediate yoke, and impinges the latter against the adjacent front side of the post 1, effectively serving to hold the adjacent side of the machine frame against the line wires and in position to receive and hold 115 the stay wires for twisting in a manner to be explained.

The post 1, carrying the perforated bar 8, is furthermore provided with arms 17 extending longitudinally with the line wires 120 and suitably bolted, as at 18, to the bar 8 and extending slightly downwardly where the upper one is bent downwardly and crosses the lower to which it is suitably secured, the outer end of the said lower inclined bar 17 having suitable clamping and guiding means 19 for engaging an adjacent line wire A, the said guide being duly shown and described in one of the aforesaid patents. Secured to the upper of the inclined bars 130

17 is a tool box 20, preferably formed of sheet metal and which may or may not be equipped with a cover, such a box having the advantage of being within convenient reach of the operator and always being carried by the machine in such position.

In the operation of the machine, it is necessary to first decide upon the style and nature of the fence desired to be built, the 10 number of line wires to be employed, and the exact distances between the same, it being the custom to arrange the lower of the line wires closer together than the upper ones for the purpose of preventing small stock from passing through the same. The line wires A are first secured in their proper spaced relation to suitable posts (not shown), and the hook-shaped bolts 12 of the machine are then adjusted in the appropriate perforations 20 11 of the bar 8 to accord with such arrangement. By turning the bolts about the axes of their shanks or stems sufficient space between the free ends of the hooks and the adjacent side of the bar 8 is provided to 25 permit of the introduction of the line wires, which may be slightly flexed to facilitate such introduction. When thus attached, the other post 1 is abutted against the wires and the sleeve 14 is forced downwardly to 30 bring the tongue 15 over the adjacent line wire A, and the machine is in attached position for the application of the first stay.

To form the stay, a pair of wires B of like gage to the line wires are cut of a length 35 slightly greater than the height of the fence, and are placed one on either side of the line wires A and located within the bifurcations 7 of the central arms 6 of the yokes, as clearly shown in Fig. 7 of the drawings. 40 The upper and lower ends C of the stay wires B are then given opposite twists about the upper and lower line wires respectively, as by means of a pair of pliers, and the intermediate portions of the stay wires between 45 each pair of adjacent line wires are then given a twisting action, as by means of any appropriate twisting tool, as indicated at D in Fig. 1, when the stay wires are caused to oppositely twist about each other and to 50 form tightly binding eyes for the line wires, and all slack is taken up and the stay caused to assume a rigid position on the line wires.

By elevating the sleeve 14 to free the tongue 15 from the line wire, the machine 55 may be moved along the line wires, the latter freely sliding through the bolts 12 until the selected position for the second stay is reached, when two more stay wires are applied as before, after properly engaging the 60 sleeve, when the operation may be repeated again and again along the entire length of the fence, when a much more powerful and durable structure than the ordinary machine-built fence, is produced.

65 From the foregoing, it will be seen that

several valuable improvements have been incorporated in the machine of the patents above stated, and that a machine simple in construction and operation for the production of hand-made wire fence has been provided which may be manufactured and sold at a cost within the reach of the small farmer.

What is claimed is:—

1. A wire fence machine for use in making 75 a fence composed of line wires and vertical stay wires, the combination of a frame having spaced vertical bars and a plurality of yokes connecting the bars provided with centrally located means for receiving and 80 holding the stay wires while being twisted, means provided on one of the bars for engaging with one of the line wires of the fence and holding the machine in fixed relation, and a perforated bar secured in spaced substantially parallel relation to the other bar and provided with a series of hook-shaped bolts to engage with the line wires.

2. A wire fence machine for use in making 90 a fence composed of line wires and vertical stays, comprising a frame having spaced vertical posts, upper and lower yokes rigidly connecting the posts in their spaced relation, a vertical bar carried by one of the posts in spaced relation thereto and extending parallel therewith, bolts traversing the post and the bar and having spacing washers or blocks thereon, said bar having a longitudinal series of perforations therein, and hook-shaped bolts having threaded shanks 100 adapted to fit any of said perforations and carrying nuts on the shanks between the post and the bar, to permit the hooks to turn to receive and to hold the line wires of the fence.

3. A wire fence machine for use in making 105 a fence composed of line wires and vertical stay wires, the combination of vertically disposed bars, a plurality of yokes connecting the bars and holding them in spaced relation, said yokes each having centrally disposed means for receiving and holding the stay wires, and a vertically slidable sleeve 110 mounted on one of the bars and adapted to clamp one of the line wires between it and the adjacent bar.

4. A wire fence machine comprising a frame having spaced vertical posts rigidly held together in spaced relation and adapted to abut against the line wires of a fence, 120 and a vertically slidable sleeve mounted on one of the posts, said sleeve being of greater internal diameter than the said posts and carrying a downwardly extending tongue having tapered side edges for engaging over one of the line wires to bind the same against the post when the sleeve is forced downwardly.

5. A wire fence machine comprising a frame having spaced vertical posts, a plu- 130

rality of yokes having terminal sleeves surrounding the posts and carrying set screws for adjusting the yokes up or down along the posts, said yokes having centrally located forks or bifurcations for receiving and holding spaced stay wires, one of said posts carrying a vertically slideable sleeve having a downwardly directed tongue for engaging a line wire and clamping the same against

the adjacent post, the other post having a plurality of swiveled hook-shaped bolts mounted in a bar held in spaced relation to the post and adapted to receive the line wires and to hold that side of the frame thereto.

In testimony, that I claim the foregoing 15 as my own, I have hereto affixed my signature.

ISAAC NEWTON MORFORD.
